UNITED STATES PATENT OFFICE.

SAMUEL FARBER AND GEORGE G. CROUCH, OF ATLANTA, GEORGIA.

MACHINE FOR CLEANING RUGS, &c.

1,204,964.

Specification of Letters Patent. Patented Nov. 14, 1916.

Application filed April 21, 1916. Serial No. 92,786.

To all whom it may concern:

Be it known that we, SAMUEL FARBER and GEORGE G. CROUCH, citizens of the United States, residing at Atlanta, in the county of Fulton and State of Georgia, have invented certain new and useful Improvements in Machines for Cleaning Rugs, &c.; and we do hereby declare the following to be a full, clear, and exact description of the invention, such as will enable others skilled in the art to which it appertains to make and use the same.

This invention relates to brushing and scrubbing, and more especially to carpet cleaners; and the object of the same is to produce a machine in which a carpet or rug can be cleaned and dried.

Another object is to provide means coacting with the machine for handling the rug after it is cleaned, or for dyeing it.

These objects are carried out in a manner fully described in the following specification, and shown in the drawings wherein—

Figure 1 is a front elevation of this machine with certain parts broken away and in section. Fig. 2 is a right side elevation and Fig. 3 is a central longitudinal section. Fig. 4 is a perspective view of the vat partly broken away, and Figs. 5 and 6 are detailed views of certain rollers. Fig. 7 is a side elevation, and Fig. 8 a plan view of the clamp referred to hereinafter.

On suitable legs 1 is carried a pair of sills 2 on which are supported side plates 3, and the sills and plates are connected by transverse members which hold them rigidly spaced, but which need not be described in detail. On a shelf 4 connecting the side plates are a number of tanks 5 from which lead pipes 6 having individual faucets 7 uniting as at 8 where they communicate with the interior of a sprinkler 9 which extends across the space between the side plates and has a row of outlet perforations 10 near its bottom. Various and different liquids can be put in the several tanks, and by manipulating the faucets any desired combination or proportions of these liquids can be allowed to flow into the sprinkler and out its perforations 10.

A rotary brush 11 stands beneath the sprinkler. Its core 12 preferably has trunnions 13 each of which is removably seated in a socket 14 in the inner end of a short shaft 15, and held therein by a set screw 16. One of the side plates is broken away in

Fig. 1 to show that said shaft is mounted in a journal box 17 which is guided vertically in an opening 18 in the side plate, and any suitable means may be employed for adjusting the two boxes 17.

The adjusting means shown herein (and duplicated on the upper wringer roller referred to below) consists of a set screw 20 threaded through a strap 21 across the opening 18, and its lower end swiveled in a socket 22 within the box 17. As shown in Fig. 1 the swivel is produced by forming a narrow groove 23 around the screw, and passing a pin or screw 24 into the box so that its tip 70 will engage said groove. The upper end of the screw 20 is formed into a hand wheel 29 whose rise and fall is limited by the top of the opening 18 and the position of the strap 21, and it is obvious that by turning this 75 hand wheel in the proper direction the box 17 may be adjusted higher or lower and the brush or the wringer roller carried with it. Directly beneath said brush is mounted a pin roll 26 whose shaft 25 is connected with 80 the shaft of the brush by gears 27 bearing a ratio of about five to one, so that when power is applied to said shaft 15 from any suitable source, such as the power shaft 28, the brush will rotate quite rapidly in one direction and 85 the pin roll rather slowly in the opposite direction as indicated by the arrows in Fig. 2. This roll is studded with brass pins to hold the rug or carpet in place and keep it from slipping backward or forward during the 90 operation of cleaning.

The wringer is composed of a lower roller 36 mounted in fixed bearings, and an upper roller 32 standing above it and whose shaft 35 is mounted in bearings which may well be 95 adjustable in the manner already described, whereby the upper roller can be borne down onto the lower with sufficient force to wring out liquid from any rug or carpet which is passed between these rollers. The upper 100 roller runs idly, while the lower roller has a sprocket 37 on one end of its shaft. The wringer stands in rear of the brush, and these elements are separated by a hanging spatter-guard 38.

The feed mechanism comprises an endless belt or apron 40 made of brass or copper mesh, and front and rear rollers 41 and 42 around which it passes. The apron also passes between the wringer rollers and over 110 the roll 26 whose pins or studs project through it. The feed rollers 41 and 42 re-

spectively carry sprocket wheels 43 and 44, and over them passes a sprocket chain 45 which also engages a sprocket wheel 46 on the shaft 25 of the pin roller, whereby power is communicated to this chain and from it to the several rollers. We have not considered it necessary to show the means for conveying power to the shaft 28, and causing it to rotate in either direction at will and at the desired speed. A second spatter-guard 48 is suspended forward of the sprinkler 9 and the brush roll, with its lower edge normally in contact with the apron 40 as best seen in Fig. 3, but this guard may be raised and held upward by a support 49 as seen in Fig. 2 when a rug or carpet is to be introduced into the machine as indicated by the arrow in this view. A vat 50 receives the drippings and soiled water, and eventually receives the rug, and by preference this vat has a box-shaped body as best seen in Fig. 4, mounted on caster wheels 51 so that it can be moved in between the sets of legs 1 and under the machine above described, and can be moved out and over the floor of the shop at will. The box has a true bottom 52 and a false bottom 53, the latter being perforated and raised above the true bottom by suitable supports 54. A faucet or other device 55 may be employed for drawing off the water from time to time. In slots 56 in the walls of the vat may be removably journaled the trunnions of a roller 57 or a pole 58 as seen in Fig. 6; or one trunnion of the roller or one end of the pole may lie in one slot while the other trunnion or end may be removably connected in any suitable manner with a crank handle 60, as by means of a socket and set screw 59 as seen in Fig. 5. As thus far described, the vat is useful for catching the soiled water, which of course passes through the false bottom 53, and the carpet or rug after cleaning can be passed over the rear roller 42 and wound onto the roller 57 or pole 58 within the vat. The vat can then be drawn out of place, and the wound roller subsequently lifted out and the carpet or rug either removed from the roller or delivered to its owner on the pole. We therefore preferably provide the roller with hooks 57 and the pole with hooks 58' with which the edge of the rug is engaged when it first passes over the rear roller 42, and after being rolled up it is tied in a manner well understood.

Drying mechanism is preferably interposed between the washing mechanism and the vat, and as herein shown this drying mechanism is carried by the side plates 3 of the machine above described, although it is operated by hand. The numeral 61 indicates a drying cylinder mounted for free rotation in bearings or extensions 63 rising from the side plates 3, 62 is a pipe admit-

ting steam to the interior of this cylinder, 64 is a cock for drawing off condensation, and 65 designates a safety valve. Journaled in the side plates 3 are the trunnions of two rollers 66 and 67, preferably squared at one end for the selective application of a crank handle 68, and the rotation of that roller from which the crank has been removed is capable of being retarded by a brake of any suitable character as indicated herein at 69, 75 the brakes in turn being controlled by ped- als 70.

In Figs. 7 and 8 is shown one of two clamps which we preferably employ. Each has two arms 71 connected at one end by 80 a hinge 72 and at the other end by a detachable clasp 73, and the contiguous faces of these arms are provided with pins 74. In their edges are rings 75 as shown, and with these are to be engaged hooks 76 at 85 the lower ends of chains 77 which pass upward behind a roller 78, in rear of the tanks 5, and lead thence over the cylinder 61 and downward to rings 79 on the rear roller 67. To the rings 75 of the other clamp are 90 also adapted to be connected hooks 86 at the lower ends of other chains 87 which lead upward over the forward roller 66 and are connected with rings 89 therein—all as best seen in Fig. 3.

The operation of the machine as thus far described is as follows: The forward spatter-guard 48 is raised and propped up as seen at 49. The rug to be cleaned is fed into the machine as indicated by the arrow in Fig. 2, and is passed over the forward roller 41 onto the apron 40. Power is then applied to drive the parts in the direction indicated by the arrows, and a proper cleansing liquid or combination of liquids is admitted through pipe 8 to the sprinkler 9, whose line of perforations 10 delivers it to the brush, which latter is rotating about five times as fast as the pin roll which in turn moves with the apron 40 carrying the 110 rug. The spatter-guards 38 and 48 (now lowered) prevent the spattering of liquid from the bristles which are moved very rapidly over the face of the rug in the presence of the dripping liquid. The parts turn in 115 the direction of the arrow until the rug passes inward and its rear end passes over the roller 42 and down into the vat 50, but just before its front end is passed from between the pin roll and brush, the direction 120 of rotation is reversed so that the rug moves forward and its front end hangs over the roller 41 into the vat 50. This to-and-fro action is continued until the surface of the rug has been thoroughly cleansed, and just 125 before its last movement to the rear the set screws controlling the wringer roller 32 are adjusted so that this roller is set nearer to the roller 36 beneath it, and in its next rearward movement the rug is squeezed between 130

these rollers and the soiled water is wrung out of it and falls into the vat. One of the clamps above described is now engaged with the rear edge of the rug and its clasp 73 fastened, and the hooks 76 on chain 77 engaged with its rings 75. The crank handle 68 is then applied to the rear roller 67 and turned, and when the rug is fed farther through the wringer it can be drawn upward by the chains 77 and over the drying cylinder 61. Finally the other clamp is attached to the edge of the rug when it passes through the wringer, and the hooks 86 on the other chains 87 engaged with the rings 75 of this clamp. Assuming now that steam is turned into the drying cylinder so that it is hot, the crank 68 is manipulated to slide the moist rug to the rear over this cylinder, a braking action being applied meanwhile to the roller 66 as soon as the chains 87 are drawn tight. The crank handle is then placed on the trunnion of this roller and the foot on the other pedal 70, and by proper manipulation the rug can be drawn back over the cylinder 61 in the opposite direction. This process is repeated until all parts of the rug have been thoroughly dried, when it is drawn to the rear over the cylinder 61 for the last time, one of the clamps removed and that edge of the rug carried downward into the box-like body 50 of the vat and attached to the hooks on either the roller 57 or pole 58. Rotation of the crank 60 now draws the rug down and it is held taut by applying the brake to the roller 66 as will be clear, and when the other edge of the rug comes down to within reach of the operator the remaining clamp is removed so that eventually the entire rug after having been washed and dried is wound up within the vat by the crank 60.

The numeral 9' (Fig. 3) designates a sheet of metal secured at its upper edge to the sprinkler 9, hanging behind it as shown, and bent up along its lower portion into a gutter 9" preferably having a beaded edge which rests against the bristles of the roller, and the numeral 6' designates a branch pipe which may lead from one of the other pipes or from one of the tanks 5 and which preferably has its own faucet 7'. It sometimes occurs that the cleaning liquid is quite thick, and this detail is for the purpose of handling such liquid without passing it through the sprinkler 9 whose perforations 10 might become clogged thereby. Such thick liquid is passed down the pipe 6' by opening its faucet 7', and fills the gutter 9" until it overruns the beaded edge upon the brush, no matter in which direction the latter is rotating, and by said brush it is applied to the rug or carpet.

We preferably make the rear feed roller 42 hollow and perforated as shown in this

view, and admit fluid to its interior through its tubular axis 42', much as steam is admitted at 62 into the cylinder 61. When the steam is admitted it flows out the perforations in this roller and through the rug 70 or carpet, and its action thereon depends upon the condition of the steam. If the latter is moist the rug is steamed and the roller in effect becomes part of the washing mechanism. If the steam is very hot or if, in fact, hot air is supplied instead of steam, the roller 42 becomes in effect a drier.

We have thus far described the parts which enter into the cleaning and drying of the rug, and its storage within a movable vat which catches the soiled water, but an improved feature of our invention consists in the adaptability of this vat for use in dyeing a rug, carpet, or other article which has thus been cleaned. If it is to be dyed, it may need to be carried through the cleaning step of the operation, or it may not; and it is possible to have cleaning liquids in some of the tanks 5 and dyeing liquids in others. But as these are cold, we make provision for heating the liquid within the vat, whether it is the same liquid that has passed through the sprinkler or not. For this purpose a steam pipe 90 is disposed within the vat over its true bottom 52, and is capable of connection with a source of steam supply, preferably through a flexible conduit which need not be illustrated. Assuming now that the rug is first cleaned, the operation is as follows: Manipulation of the proper faucet or faucets 7 permits the flow of cleaning liquid, which in its soiled condition accumulates within the vat before the steam is turned on to the coil or pipe 90. The rug is reciprocated and washed as described, and it may be dried or not as desired. The false bottom 53 and its supports are removed from the vat, and the soiled water drawn off as at 55; or if preferred, the vat which has caught the soiled water 110 can be moved from beneath the machine and replaced by another vat whose false bottom has been taken out. Whatever vat is used in dyeing must of course have its faucet 55 closed, and the dyeing liquid will be admitted thereto from a suitable source and to a suitable depth. Steam is then turned on and the coil or pipe 90 heats this liquid. The rug is now passed down behind the roller 42 and, instead of being wound on the roller 57 or pole 58, it is submerged in the hot dyeing liquid for a sufficient length of time. If such time be considerable, this vat may be run out from under the machine and the latter employed on another rug. 120 But after the dyeing operation is completed, the chains may be employed as above described to draw the rug out of the vat and to reciprocate it over the drying cylinder in the manner hereinbefore set forth. 130

Finally it is let down in its finished condition and wound on the roller or pole as has also been described.

Thus it will be seen that the so-called 5 "vat" is a useful element in the machine, whether the rug is to be dyed or not, and in the latter case the false bottom is used and the steam is cut off.

We have spoken throughout this specification 10 of the cleaning of rugs and carpets, but it is quite obvious that other articles in sheet or strip form could be handled with equal ease.

We have been quite successful in cleaning 15 machine belts, and a number of them can be handled simultaneously by feeding them endwise into this machine and disposing them side by side across the apron 40.

It is obvious that if the article being 20 treated is such that it does not need to be wrung out, the upper wringer roller 32 can be raised so as to put this element out of action for the time.

What we claim is:

25 1. In a machine for treating rugs and the like, the combination with a feed mechanism including a plurality of rollers, an apron passing over them, and means for moving the apron to and fro; of a washing mechanism

30 including a brush rotating in conjunction with one of said rollers, an upper roller overlying the apron above another of said rollers and means for adjusting the upper roller vertically at will.

35 2. In a machine for treating rugs and the like, the combination with a feed mechanism including a plurality of rollers, an apron passing over them, and means for moving the apron to and fro; of a washing mechanism

40 including a brush rotating in conjunction with one of said rollers, an upper roller coacting with another of those first mentioned, and means for lifting the rug off the apron after it has passed said upper roller.

45 3. In a machine for treating rugs and the like, the combination with a feed mechanism including an apron, and means for moving the apron to and fro; of a cylinder mounted in bearings in rear of and above the

50 apron, and chains passing over said cylinder

der and having clamping means at one end for engaging the rug and lifting it off of said apron, and means for imparting draft to the other ends of said chains.

4. In a machine for treating rugs and the like, a framework including a pair of side plates, a shelf connecting them, tanks thereon, a perforated sprinkler between said plates, individual connections between the tank and sprinkler, and a rotary brush below the latter; combined with an apron for receiving the rug, means for supporting the apron and reciprocating it beneath said brush, spatter-guards in front and rear of said brush, and means for holding the front guard elevated at will.

5. In a machine for handling rugs and the like, the combination with a framework having upright extensions at its rear end, and a feed mechanism for carrying the rug to the rear; of a drying cylinder rotatably mounted in said extensions, means for supplying a heating fluid to its interior, two rollers journaled in the framework beneath said cylinder, a brake for application to each roller, and chains extending from the rollers and one of them adapted to lead over said cylinder.

6. In a machine for handling rugs and the like, the combination with a framework having upright extensions at its rear end, and a feed mechanism for carrying the rug to the rear; of a drying cylinder rotatably mounted in said extensions, means for supplying a heating fluid to its interior, two rollers journaled in the framework beneath said cylinder, a brake for application to each roller at will, a series of chains leading from one roller and having hooks at their outer ends, a series of chains leading from the other roller over the cylinder and having hooks at their outer ends, and two rug-clamps, each having a series of rings for engagement by the hooks on one series of chains.

In testimony whereof we affix our signatures.

SAMUEL FARBER.
GEORGE G. CROUCH.
